J. HENRY CHAMPLIN, OF ESSEX, CONNECTICUT

Letters Patent No. 74,501, dated February 18, 1868.

IMPROVEMENT IN SPIKES.

The Schedule referred to in these Letters Patent and making part of the same.

TO ALL WHOM IT MAY CONCERN:

Be it known that I, J. HENRY CHAMPLIN, of Essex, in the county of Middlesex, and State of Connecticut, have invented a new Improvement in Spikes; and I do hereby declare the following, when taken in connection with the accompanying drawing and the letters of reference marked thereon, to be a full, clear, and exact description of the same, and which said drawing constitutes part of this specification, and represents a perspective view.

The nature of my invention relates to an improvement in the construction of spikes, such as are used on railroads, ship-building, and other purposes, and consists in cutting out a portion of the spike at any given distances apart, on the angle of the same, inclining the slot or notch downward and into the body of the spike, so as to leave a sharp point of the edge or angle of the spike below the upper end of the slot, but not to project beyond the line of the spike, as will be hereinafter described.

In order that others skilled in the art may make and use my invention, I will proceed to describe its construction and operation.

In the drawing, A the spike, provided with a head, B, of any size adapted to the use for which the spike is designed. The spike is formed from square metal in the usual manner, presenting a four-sided spike, the sides at right angles, with the point somewhat sharpened, and at given distances on each angle or corner of the spike A, slots or notches *a a a a* are cut into the spike, cutting out a part of the spike. This slot is wider at its upper and outer edge than at its lower and inner point, where it is brought to a sharp point, and is at an angle of about forty-five degrees with the line or angle of the spike, thus leaving a sharp point, cone-shaped, projecting up above the lower point of the slot, about half an inch or more, according to the size of the spike. The sharp point or cone thus formed never projects beyond the line of the angle, and never enlarges the width of the spike. These points are formed by cutting away relative portions of the spike directly at the angles or corners, leaving then, from their position on the spike, a three-sided cone or hook on the angles of the spike, and cannot be made at any other point or part of the spike.

The spike thus formed may be driven in the usual manner; the points or hooks do not prevent its entrance into the wood. The pressure of the spike in entering the wood by the blows of the operator, forces the fibres of the wood out alike on all sides, compressing the same equally at all points affected by the blows; and, when driven to its desired point, in a short time the wood will expand opposite the slots on each angle, and press firmly down and into the slots or notches above and over the points, catching on them; and when the wood swells and regains in part its position from which it was forced by the driving of the spike, great resistance will be offered to the withdrawing of the spike, in proportion to the strength of the fibres of the wood that have filled the slots.

It will be seen that, in spikes made with the barbs projecting out from the body of the spike, that they are much harder to drive into the wood than is my invention, and as the spikes with such barbs are driven down into the wood, they will cut the fibres of the wood into short sections, thus weakening the fibres of the wood, and making but little resistance on the part of the wood against which they catch, thus destroying the very purpose for which they were intended.

In my invention, the point or hook intended to hold and offer resistance in being withdrawn, does not project, but is on the same line with the angles or corners of the spike; they offer no additional resistance in driving, nor do they cut the fibres of the wood into short sections, but only force them back uncut by the hooks, so that as the wood swells, and vibrations are caused by the weight of the train passing, the fibres fall into the slots *a a* with all the strength of the wood with its uncut fibres.

My spike will be found of great value for railroad purposes, as it will not be liable to work loose by the pressure of the train passing over it, and also for all like purposes, and it is driven as easily as a plain spike.

I am aware that barbed spikes have been used. I do not claim a barbed spike, but a slotted or notched spike, as above described.

Having thus described my invention, what I claim as new, and desire to secure by Letters Patent, is—

The spike A, constructed with slots or notches *a a a a*, cut into the body of the same at its several angles, substantially as described, and as and for the purposes set forth.

J. HENRY CHAMPLIN.
